(57) CLAIM

The ornamental design for a zipper pull, as shown and described.

DESCRIPTION

FIG. 1 is a front, left perspective view of a zipper pull with portions other than a front outer perimeter of the zipper pull shown in broken lines.

FIG. 2 is a front elevation view of the zipper pull of FIG. 1 with portions other than a front outer perimeter of the zipper pull shown in broken lines.

FIG. 3 is a rear elevation view of the zipper pull of FIG. 1 with the rear portions shown in broken lines.

FIG. 4 is a right side elevation view of the zipper pull of FIG. 1 with portions other than the front outer perimeter of the zipper pull shown in broken lines.

FIG. 5 is a left side elevation view of the zipper pull of FIG. 1 with portions other than the front outer perimeter of the zipper pull shown in broken lines.

FIG. 6 is a top plan view of the zipper pull of FIG. 1 with portions other than the front outer perimeter of the zipper pull shown in broken lines.

FIG. 7 is a bottom plan view of the zipper pull of FIG. 1 with portions other than the front outer perimeter of the zipper pull shown in broken lines.

FIG. 8 is a rear, left perspective view of a second embodiment of a zipper pull with portions other than a rear outer perimeter of the zipper pull shown in broken lines.

FIG. 9 is a front elevation view of the zipper pull of FIG. 8 with front portions shown in broken lines.

FIG. 10 is a rear elevation view of the zipper pull of FIG. 8 with portions other than a rear outer perimeter of the zipper pull shown in broken lines.

FIG. 11 is a right side elevation view of the zipper pull of FIG. 8 with portions other than the rear outer perimeter of the zipper pull shown in broken lines.

FIG. 12 is a left side elevation view of the zipper pull of FIG. 8 with portions other than the rear outer perimeter of the zipper pull shown in broken lines.

FIG. 13 is a top plan view of the zipper pull of FIG. 8 with portions other than the rear outer perimeter of the zipper pull shown in broken lines; and,

FIG. 14 is a bottom plan view of the zipper pull of FIG. 8 with portions other than the rear outer perimeter of the zipper pull shown in broken lines.

The broken lines in FIGS. 1-14 illustrate portions of the zipper pull that form no part of the claimed design.
